HYDRAULIC PRESS

Filed Aug. 13, 1938

UNITED STATES PATENT OFFICE

2,254,613

HYDRAULIC PRESS

Irving Frederick Matthysse, New York, N. Y.

Application August 13, 1938, Serial No. 224,820

3 Claims. (Cl. 140—113)

The present invention relates to a portable hydraulic press in which the pump and reserve oil reservoir are combined with the press itself as a single assembly. A press of this type is very useful in the electrical utility industry for use in conjunction with electrical connectors for making connections in transmission and distribution lines, both underground and overhead. In addition, it may be used for a variety of other purposes—as a punch, as a cable or bolt cutter, etc. Its usefulness is by no means limited to the electrical industry; it may be used for any one of the numerous applications which might call for a small portable press.

An efficient method of making electrical connections in electrical cables is to insert the ends of the cable into the ends of a close fitting tube and indent the tube onto the cable ends. This method has been used widely where the cable connections have been made as factory assemblies and heavy stationary presses could be used to indent the connectors onto the cables. However, where connections had to be made in transmission and distribution systems in the field, presses light enough to be conveniently used were not available. The weight of the press is of special importance where connections must be made on overhead lines. A man working on a pole top must have a light easily handled device to operate. In order to be readily used the press should weigh less than ten pounds.

Therefore, one object of the present invention is to provide a complete, self-contained press, which is portable and which can be easily carried by a linesman to the top of a pole.

In making electrical connections underground, such connections must many times be made in small manholes or "hand holes." Because of the lack of space in such "hand holes" any tool which must be used therein must be small and compact. Similarly, where installations must be made overhead on live lines, it is important that the tool should not be as long as the clearance between phases. If the tool were that long, a careless lineman might short the phases with the tool and a serious accident might result.

Another object of this invention, therefore, is to provide a short, compact tool.

For each size of cable there is an indentation with an optimum depth of impression for efficient gripping of the conductor. The proper depth may be determined for each cable size by experimentation. Once this value is found, it is desirable that all indentations on the same cable size be of the same depth. It is quite

difficult for the lineman on a pole top or a splicer in an underground vault to know exactly how deep the punch has penetrated into the connector. Therefore, an automatic arrangement is necessary to relieve the pressure exerted by the tool when the punch has penetrated to the proper depth.

Another object of this invention, therefore, is to obtain a press whereby the length of travel of the punch is automatically determined.

Because of the awkward positions in which linemen or splicers, overhead or underground, must work with this device, and the repeated indentations they must make with it, it must be easily operated. This requires a considerable mechanical advantage and a high efficiency. In order to reduce the relatively large losses due to friction, a hydraulically operated tool was found to be most efficient. In addition, the mechanical advantage of the tool can be easily regulated in a hydraulic device.

Another object of this invention, therefore, is to provide a hand actuated device which can be operated with a minimum of fatigue.

In order for a hydraulic press to function properly, air must be excluded from the portion containing fluid which is under pressure. Inasmuch as air is compressible, if it were to get into the pressure chamber, it would act as a cushion and prevent the pressure from building up quickly. Unlike other hydraulic devices, where the pump is either a separate unit, or is permanently located so that the air cannot get past the fluid reservoir, this invention combines both pump and press and is designed to be used in any position and at any angle. To accomplish this, I have devised a follow-up piston which makes the entire hydraulic system a closed system, so that air cannot penetrate into either the pressure chamber or the reservoir.

Therefore, a still further object of my invention is to obtain a device which can be operated in any position and any angle without air getting into the pressure chamber and acting as a cushion.

In joining cables on end into a continuous length it must be possible to remove the tool after the connection has been made. This may be accomplished in a variety of ways. The working head of the tool may have a replaceable die which can be slipped out in order to permit removal of this tool from the joined conductor. Another way is to make the working head in the form of a hook.

Another object of my invention, therefore, is

to obtain a device that can be readily removed from the conductor after the connection has been completed.

After the indentation is made and the hydraulic pressure released, it is desirable that the punch automatically recede into the pressure chamber. This eliminates the necessity of manually forcing the punch back, which is an awkward and time consuming operation.

Still another object, therefore, of my invention, is to provide a punch which will automatically recede when the fluid pressure in the pressure chamber is released.

Very often connections must be made in live electrical cables. In such cases it is desirable to work with an insulated tool. Therefore, another object of my invention is to provide a portable hydraulic press that can be readily insulated.

Because of the awkward positions and cramped quarters in which my tool must often be used, I have made the working head rotatable to various angles. Therefore, another object of my invention is to provide a portable hydraulic press with a rotatable working head.

My hydraulic tool is designed to exert pressures up to approximately 18,000 pounds. However, if pressures in excess of this figure were built up within the tool by continued pumping, damage might result to the packing of the tool or even to the metal parts. Another object of my invention, therefore, is to provide an automatic relief valve which will relieve the fluid pressure in the pressure chamber when excessive values are built up therein. This is the same valve which controls the depth of penetration of the punch as previously described.

I accomplish these and other objects and obtain my new results as will be apparent from the device described in the following description, particularly pointed out in the attached claims, and illustrated in the accompanying drawing, in which:

Fig. 1 is a sectional, axial view through my device.

Fig. 2 is a top view of the same.

Fig. 3 is a side view.

Fig. 4 is a partial, sectional view taken along the line 4-4 in Fig. 1.

In the drawing, reference numeral 10 designates the portable pump, reservoir and press, illustrated in section in Fig. 1. The unique bellows-like action is accomplished by an integral handle 11, a pivoted lever 12, a body 13, and a head 14.

A holding die 15, semi-cylindrically shaped as at 16 to support the cable 17, enclosed in the sleeve 18, forming part of the connector, not shown, is provided with shoulders 19, riding in grooves 20, of the head 14. A retaining screw 21, threadedly engaging tapped hole 22, holds spring 23, forced against ball 24, which in turn is forced against an indentation 24A, in the wall of the holding die 15, to prevent the die from longitudinal movement with respect to the grooves 20.

The indentation in the cable enclosed sleeve 18, is accomplished by a ram 25 propelled under the oil pressure, to which is fitted an impression die 26 shaped with a projection 27 in the form desired. A die set-screw 28 holds the impression die to the face of the ram.

The unique bellows-like action of the device is accomplished by designing the compressing piston at right angles to the movement of the ram. This is illustrated in the piston 30, transversely

mounted in the body 13. The piston is inserted into a cylindrical recess 31, provided with a shoulder 32, upon which is seated the packing washer 33, the packing 34, all retained in position around the piston by the packing nut 35 threaded into the mouth of the recess.

The head of the piston is C shaped as at 36, engaging the piston pin 37, integrally attached to the lever 12, by means of a pair of bracket plates 10 38. A fulcrum pin 39, supported by fulcrum bracket 40, preferably formed integrally with the body 13, is carried by bracket plates 38, permitting the lever 12 to be pivotally mounted on the body. The bracket plates 38 are shaped to form the stop 41 to engage the body.

The cylindrical chamber 31 to which the piston 30 is closely fitted, terminates in a passageway 43 for allowing the oil to follow the piston in its outward motion. Transversely extending at the termination of the passageway 43 is a passage 44 into which is inserted the small ball valve 45, supported by shoulder 46 formed into the passageway, leading to channel 47, connecting the oil reservoir 48. An oil screen filter 49, is placed against the opening into the reservoir to keep foreign matter from interfering with the operation of the ball valves.

Passageway 44 terminates in a channel 50, forming shoulder 51, carrying large ball valve 52. Valve spring 53 is made up with three sections, one section 54 of small diameter for engaging small ball valve 45 for keeping it shut when the tool is operated in positions where the force of gravity will not cause the ball to drop into the proper position.

Middle section 55 is of a diameter sufficient to maintain longitudinally the three sections in axial alignment within the passageway. The remaining section 56, is of a diameter to engage properly large ball valve 52. This novelly wound spring, it has been found, will align the spring in the passageway to properly engage the ball valves without jamming between valves and seats. Channel 50 contains spring 57 for seating ball valve 52, supported by spring retainer 58, threadedly engaging the end of channel 50.

The oil flowing through channel 50 enters the ram chamber 60, formed in the body 13 by the cylindrical recess 61, into which the ram 25 is slidably moveable. The ram is provided with peripherally formed shoulders 62, supporting the ram packing 63, in turn covered by ram spring washer 64 and compressed by ram nut 65, threadedly engaging the end of the ram and provided with a central recess 66 substantially the same diameter as a central recess 67 within the ram itself, extending longitudinally to a point near the ram face 68 and terminating in the wall 69. A ram set-screw 70 locks the ram nut to the ram. Within the central bore 67 of the ram is housed the ram return spring 71, carried about pin 72, having a flat head 73 integral therewith for supporting the spring 71. The other end of the spring is supported on the head 65A of the ram nut 65, which is apertured as at 65B to permit the free flow of the oil therethrough. The pin 72 may be milled with two flat surfaces 72A to facilitate assembly of the ram to the body, 13.

The remaining end of the pin is longitudinally slotted as at 74 to permit the flow of oil therethrough (see Fig. 4) and threadedly engages a tapped channel 75 forming an oil return. A guide screw 76 projecting through a tapped aper-

ture 11 in the side of head 14, provides a longitudinal guide for ram 25 by riding on slot 77A.

The head 14 of the press is internally threaded as at 78 engaging the externally threaded section 79 of the body 13. The head and body are rotatably mounted thereon with head stop screw 80 inserted through a tapped aperture 81 in the head for engaging the two sides of a 90 degree cut-out (not shown) in the wall 82 of the body 13. A frictional movement of the head through 90 degrees is thus provided.

In Fig. 4, the sectional view shown is normal to that shown in Fig. 1. Two attachments are there illustrated, namely a pressure relief or overload valve 90 and a manual release valve 91, the latter of which controls the channel 75, the oil return. Connecting with channel 75 is passageway 96 provided with a beveled shoulder 92 on which is seated the cone shaped valve 93, of stem 94, to which the manual release knob 95 is integrally connected.

The valve stem has a narrowed section 96, to permit the oil to flow around it when the valve 93 is lifted off its seat 92. The transverse recess 97 houses the valve stem 94, to which a channel 98 connects, permitting the oil to flow into the reservoir 48. In the upper portion of recess 99, are provided shoulders 100 into which is fitted valve packing 101. A packing nut 102, externally threaded at 103, is provided with a tapped bore 104 permitting the upper threaded section 105 of the valve stem 94 to be threadedly inserted. The packing nut is inserted into the upper tapped bore 106 of recess 99 to compress the packing, rendering the valve leak-proof. A stop screw 107 is inserted into the packing nut through transverse threaded passage 108, to prevent the valve stem 94 from being completely removed. This is accomplished by allowing the narrowed section 109 of the stem to abut the stop screw 107 in its open position. When the stop screw 107 is completely inserted, it acts as a lock to prevent any movement of the valve stem.

The overload valve 90, comprises a cylindrical section 120, loosely fitted in the oil channel 121 having a cone-shaped valve 122 engaging the seat 123 extending therefrom and a guide stem 124 loosely fitted in a tubular section 125 extending from nut 126 externally threaded at 127 into the threaded terminal 128 of the oil channel 121. Apertures 129 in nut 126 allow the oil to flow through the oil channel 121 into the reservoir 48. A pressure spring 130 is supported at one end by nut 126 and the other end engages the shoulder 131 of the cylindrical valve section 120 forcing the valve 122 against seat 123. The tubular handle 11 is hollow and is externally threaded at one end 140, to engage the internally threaded bore 141 of the reservoir cap 142. The body 13 is externally threaded to receive the threaded cap 142. Within the hollow handle 11 is a filler cap 143 having a projecting threaded stem 144, for threadedly closing the threaded end 145 of the follow-up hollow piston 146. A washer 147, prevents leakage between the cap 143 and piston 146. The head 148 slidably fits the internal cylindrical reservoir 48, and on shoulders 149, is provided with packing 150 compressed by packing nut 151. Follow-up spring 152 forces the follow-up piston into the reservoir 48 against pin 153 inserted into holes 154 in handle 11, catching a coil of the remaining end of the spring.

Operation

The outward movement of piston 30 forces oil from the reservoir 48 past ball valve 45 into the piston chamber 31. Downward movement of the piston forces the oil out of the piston chamber into the ram chamber 60, opening ball valve 52 against the action of its spring 51. The ram moves forward by the added volume of oil. This action continues until the desired indentation or tool action is completed.

When the tool is to be reset, the oil is released from the ram chamber by manually operating the release knob 95 which lifts the valve 93 from its seat 92 permitting the ram return spring, 71, to draw back ram 25, thus forcing the oil to flow from the ram chamber 60 back into the reservoir 48, through slots 74, channel 75 and 98.

In the event the pressure in the ram chamber 60 exceeds the rated pressure, relief valve 90 opens against spring 130 to permit the oil to escape back into the reservoir, reducing the pressure to the capacity of spring 130. This action is automatic.

To avoid the entrance of air into the press, which might accumulate in the piston chamber 30 and effectively prevent the rapid pressure build-up, the follow up piston 146 is provided. It follows the reduction in volume in the reservoir under action of spring 152, permitting the oil to be withdrawn into the piston and ram chambers. Any type of expanding and contracting chamber for excluding air from the oil reservoir may be used, such as a flexible diaphragm, chamber or bellows.

A layer of insulating material 155 completely covers all exposed surfaces, as shown, to prevent electrical shock or short circuit. Shield 156, is provided as an additional precaution.

While the shoulder, 76A limits the depth of penetration permitting the oil pressure to automatically build up until the overload valve operates, the invention contemplates devices in which a lever connected with the ram, will trip valve 90 releasing the oil, without building up to the overload pressure. Furthermore, while a single piston is shown, a double acting piston, or a double piston may be used to accelerate the action. And whereas the handle 11, is shown integral with the body, it may be made pivoted, as at 39, and connected with its own piston.

It can thus be readily seen that I have accomplished all the foregoing objects of my invention. Instead of a separate press and oil reservoir, hitherto used for the foregoing purpose, I have combined them into a single assembly. The weight of the press described, and shown in the drawing, is approximately ten pounds—light enough for any operator. It is small enough to fit into any box or handhole where it is desired to compress a connector to a conductor. It is compactly and efficiently designed to permit ease of operation from any position or angle, the bellows-like action facilitating manual operation of the lever and handle. It is short enough to permit clearance between phases on the lines. Set screws and stops determine the maximum penetration, and in addition permit the head to rotate with respect to the handle, where required. An important result obtained is the complete exclusion of all air, which might result in loss of efficiency. The device is operable from any position or any angle without air leakage, and may be installed on the cable and readily removed therefrom after the connection

has been made. After the proper pressure or depth of penetration has been reached, the punch will automatically recede.

I have thus described my invention, but I desire it understood that it is not confined to the particular forms or uses shown and described, the same being merely illustrative, and that the invention may be carried out in other ways without departing from the spirit of my invention, and, therefore, I claim broadly the right to employ all equivalent instrumentalities coming within the scope of the appended claims, and by means of which, objects of my invention are attained and new results accomplished, as it is obvious that the particular embodiments herein shown and described are only some of the many that can be employed to attain these objects and accomplish these results.

What I claim and desire to secure by Letters Patent is as follows:

1. A hydraulic press comprising a body having an oil reservoir, a ram, a chamber therefor, a piston for forcing the oil from the reservoir into the ram chamber for propelling the ram, and a

head rotatably mounted on said body for supporting the object to be pressed and attached to said ram and rotatable therewith as a unit, independently of said body and without loosening 5 therefrom.

2. A hydraulic press comprising a body having an oil reservoir, a ram, a chamber therefor, a piston for forcing the oil from the reservoir into the ram chamber for propelling the ram, and a head rotatably mounted on said body for supporting the object to be pressed and having stop 10 means thereon for terminating the movement of the head with respect to the body, a predetermined amount in either direction.

3. A hydraulic press comprising a body having an oil reservoir, a ram, a chamber therefor, a piston for forcing the oil from the reservoir into the ram chamber for propelling the ram; a spring for automatically returning the ram to its starting position and assembled to said ram and removable from the body as an assembled 15 unit; and a head for supporting the object to be pressed.

IRVING FREDERICK MATTHYSSE.
